(57) **CLAIM**

The ornamental design for a wing nut anchor having discontinuous threads, as shown and described.

DESCRIPTION

FIG. 1 is a perspective view of a wing nut anchor having discontinuous threads;

FIG. 2 is a front view of the wing nut anchor having discontinuous threads, the rear view being identical thereto;

FIG. 3 is a left side view of the wing nut anchor having discontinuous threads, the right side view being identical thereto;

FIG. 4 is a top view of the wing nut anchor having discontinuous threads; and,

FIG. 5 is a bottom view of the wing nut anchor having discontinuous threads.

The broken away symbols in the drawings indicate that any portion of the article beyond what is shown forms no part of the claimed design.

1 Claim, 4 Drawing Sheets
